UNITED STATES PATENT OFFICE.

RICHARD H. VESEY, OF IDAHO SPRINGS, COLORADO, ASSIGNOR OF ONE FOURTH TO GEORGE S. SANDERSON AND WALTER S. SANDERSON, OF DENVER, COLORADO.

TAMPING-PLUG.

SPECIFICATION forming part of Letters Patent No. 650,804, dated May 29, 1900.

Application filed June 6, 1899. Serial No. 719,553. (No model.)

To all whom it may concern:

Be it known that I, RICHARD H. VESEY, a citizen of the United States of America, residing at Idaho Springs, in the county of Clear Creek and State of Colorado, have invented 5 certain new and useful Improvements in Tamping-Plugs; and I do declare the following to be a full, clear, and exact description of the invention, such as will enable others skilled in the art to which it appertains to 10 make and use the same, reference being had to the accompanying drawings, and to the letters and figures of reference marked thereon, which form a part of this specification.

15 My invention relates to improvements in tamping-plugs of the class set forth in my pending application, Serial No. 699,223.

My improved tamping-plug is formed from a cylindrical piece of wood, which is first bored 20 longitudinally to form a fuse-opening and then sawed diagonally until the wedge-shaped parts on opposite sides of the saw-cut are nearly severed, enough of the wooden fiber, however, being left uncut to hold the two 25 parts together temporarily for convenience of handling and to facilitate insertion in the drill-hole of the rock, the saw-cut extending into the fuse-opening, the arrangement being such that when the two parts are separated 30 the portion of the fuse-opening in one part is open on one side to allow the said part to move away from the fuse without disturbing the latter. This uncut portion of the wood is at the outer extremity of the plug and may 35 be easily broken by a hammer-blow after the plug is inserted. The piece of the plug having its thick end outermost is then driven inwardly and the plug fastened in the hole by a wedging action, since the inclined faces 40 formed by the diagonal saw-cut are in engagement with each other.

The invention will now be described in detail, reference being made to the accompanying drawings, in which is illustrated an embodiment thereof.

45 In the drawings, Figure 1 is a side elevation of my improved tamping-plug. Fig. 2 is a longitudinal section taken through the

same. Figs. 3 and 4 are sections taken on the lines X X and Y Y, respectively. Figs. 5 and 6 are detail views of the two wedge-shaped parts of the tamping-plug shown separately from each other.

Similar reference characters indicating corresponding parts in the views, let the numerals 5 designate the plug, which is sawed on the diagonal line 6 to a point 7, the unsawed part 8, which is indicated by a dotted line, (see Fig. 1,) being only of sufficient strength to hold the two parts 5^a and 5^c temporarily together. When the plug is inserted, the uncut end is outermost. It will be readily understood that a blow delivered upon the thick end A of the part 5^c will break the uncut fiber 8 and allow the part 5^c to move inwardly whereby the plug is wedged tightly in the drill-hole. The thin end of the part 5^c is cut off, as shown at B, to prevent it from coming in contact with the powder as it is driven inwardly toward the dynamite charge.

The fuse-opening C, which extends entirely through the plug, is formed to one side thereof, so that only a small portion of it is in the part 5^c. This portion of the fuse-opening in the part 5^c is open on one side (see Fig. 6) to permit the part 5^c to move away from the fuse without disturbing it as the said part moves inwardly in the performance of its function. The cap 9, which is located in the part 5^a at the inner extremity of the fuse-opening, is connected with the fuse by means of a piece of tube 10, composed of rubber or similar material, which forms a water-tight joint, preventing the water from entering the cap around the fuse.

Having thus described my invention, what I claim is—

1. A tamping-plug provided with a fuse-opening extending longitudinally therethrough, said plug being sawed diagonally nearly through, enough material being left uncut to hold the two wedge-shaped parts together, the saw-cut extending into the fuse-opening, the arrangement being such that when the two parts are separated the portion of the fuse-opening in one part is open on one

side to allow the said part to move away from the fuse without disturbing the latter.

2. A tamping-plug having a fuse-opening extending longitudinally therethrough, said plug being composed of two parts having inclined engaging faces, the fuse-opening in one part being open on one side adjacent the inclined face to allow the said part to move

away from the fuse without disturbing the latter during the tightening operation. ¹⁰

In testimony whereof I affix my signature in presence of two witnesses.

RICHARD H. VESEY.
